SHEET-REGISTER

Charles W. Harrold, Cleveland, Ohio, assignor to
 Harris-Seybold-Potter Company, Cleveland,
 Ohio, a corporation of Delaware

Application November 19, 1932, Serial No. 643,403

18 Claims. (Cl. 271—59)

My invention relates generally to paper feeding machines, and more particularly to certain improvements in sheet registering devices especially side-register guides for gaging the position of the successive sheets accurately in such machines.

The objects of my invention are, among other things, to provide an improved side register guide that is capable of operating at high speeds and 10 is also devised to position the sheets in perfect registry by holding each sheet between two parallel surfaces to prevent curling or crumpling at the point where such sheet contacts with a fixed register gage as the sheet is drawn thereto by 15 means of coating pulling wheels and a subjacent movable bar. In such improved device one of the parallel faces is held stationary while the other is moving with the sheet positioned by the movable bar until the sheet strikes the fixed side 20 gage where it is held flat and supported at the point of contact with this gage while the movable bar slides under such sheet.

My improved sheet-register embodies other features of novelty and improvement whereby 25 the device is rendered simpler and otherwise better adapted and more convenient for use, all of which will be hereinafter described and claimed.

In the accompanying drawings illustrating a preferred embodiment of my invention, Fig. 1 is 30 an end elevation of the improved sheet register looking down the feeder and showing the cam connection in operative position;

Fig. 2 is a side elevation looking from the right of Fig. 1 and showing the cam operating mechanism and the position of the side guide to the paper feed line;

Fig. 3 is an enlarged view on the line 3—3 of Fig. 1;

Fig. 4 is an enlarged detail section on the line 40 4—4 of Fig. 1 showing the adjustments for different widths of sheets;

Fig. 5 is an enlarged section on the line 5—5 of Fig. 3; and Fig. 6 is a view similar to Fig. 1 showing the parts as the sliding bar is moving 45 to the right beneath the sheet registered against the side gage.

Similar numerals refer to similar parts throughout the several figures.

Referring to the figures, the side-frame 6 of 50 the feeder supports the register side guide as a whole along with the bar 7 extending across the width of the machine and carrying the side register mechanism. The shaft 8 (driven from any suitable source of power) is timed to revolve one 55 for one with the setting of the successive sheets.

Keyed to the shaft 8 is the side-guide cam 9 that actuates the mechanism for reciprocating the side guide back and forth across the path of the sheets to bring same into proper side registry.

Such mechanism comprises the cam-rollers 10 and 11 pinned to the arm 12 which is pivoted on the bracket 12^a fast to the side-frame 6, the arm 12 being interchangeably connected to the arm 13 by the pawl 14 pinned to the arm 13 with the pawl 14 engaging the ends of the notch 15 cut in the upper end of the arm 12 (Fig. 1). The arm 13 is connected to the sliding bar 16 carried in the bar 7 by the bracket 17 and pin 18 carried at the end of the arm 13. The spring 19 connected to the arm 13 pulls this mechanism in 15 one direction to cause the roller 11 to follow the cam 9 with the sheet registered against the fixed side-gage 20 as shown in Fig. 1.

When the pawl 14 is shifted to the left end of the notch 15 (Fig. 1), the roller 10 is brought 20 into contact with the cam 9 (the roller 11 being then disengaged), and the spring 19 is shifted to connect with the pin 21 so that the sheets may be registered against the opposite left-hand gage (not shown) in the same manner as against 25 the gage 20.

The cam-shaft 22 (Figs. 1 and 2) is rotated once for each operation of the side guide devices and carries the cam 23 which engages the cam-roller 24 pinned to the arm 25 pivoted to the 30 bracket 26 secured to the bar 7. The upper end of the arm 25 is connected by the link 27 to the rock arm 28 carried by the rock-shaft 29 on which is adjustably secured the lever 30 which engages the lever 31 which actuates the upper plate 32 of the register mechanism arranged above the path 35 of the sheets. The lever 31 is provided with the pin 33 (Figs. 1 and 2) that may be engaged by the hook 34 to lock the lever 31 in inoperative position when desired. The register mechanism is operated by the arm 25 in one direction while the spring 35 causes the cam-roller 24 to follow the cam 23 to operate the arm 25 in the opposite direction. The spring 35 is fastened to the lever 36 keyed to the rock-shaft 29 as shown in Fig. 2. 45

Referring to Fig. 2, when the shaft 29 is rocked in a counter clockwise direction by the cam 23, the lever 31 fulcrumed on the pin 37 (Fig. 1) through the link 38 actuates the sliding member 39 carried in the bracket 40^a movably affixed to 50 the bar 7. This sliding member 39 carries a pair of pull wheels 40 having rounded peripheral edges and are journaled in the movable block 41 (Fig. 5) which is adapted to be raised and lowered in the pocket 42 and is held in position by the plate 43 55

fastened to the sliding member 39 (Fig. 5). In its lowered position the block 41 rests on the horizontal extension 44 of the sliding member 39 to which the upper plate 32 is fastened.

5. Between the block 41 and the adjusting screw 45 carried by the sliding member 39 is the coil spring 46, and the coil spring 47 of heavier construction than the spring 46 is coiled about the rod 48 fastened to the upper plate 32 and extends 10 into the pocket 49 in the bracket 40^a where the tension of the spring 47 is regulated by the screws 50 (Figs. 1 and 2). The coil spring 46 tends to keep the block 41 seated in contact with the top surface of the extension 44 (Fig. 5), but does not 15 tend to make the plate 32 contact with the sheet of paper. The heavier coil spring 47 serves to force this plate 32 into contact with the sheet when the spring 46 is compressed thereby unseating or separating the block 41 from the extension 20 44. Hence as such block 41 is unseated from its contacting position with the extension 44, the plate 32 comes into contact with the sheet S, but only with a pressure that is the difference between the respective tensions of the two springs 25 46 and 47. Since these spring tensions are both adjustable through the screws 45 and 50, the pressure of the plate 32 on the sheet can be delicately regulated or controlled so that such plate 32 may 30 make a very light contact with the sheet, while the wheels 40 can be made to contact with the sheet S with the full tension of the coil spring 46.

When the sliding member 39 is raised away from the bar 16 by the rock-shaft 29 along with the block 41, wheels 40 and plate 32 (Fig. 5), the 35 two springs 46 and 47 are compressed but with different tensions. As the rock-shaft 29 is moved in a clockwise direction (Fig. 2), the sliding member 39 is lowered with the pull wheels 40 and plate 32 to contact with the sheet S positioned 40 between the plate 32 and the under sliding bar 16 as shown in Fig. 1. Since the spring 47 is stronger than the spring 46, the pull wheels 40 will engage the sheet and sliding bar 16 and the spring 47 continue the lowering movement of the 45 plate 32 while the block 41 moves upwardly in the pocket 42 so as to bring the plate 32 into contact with the sliding bar 16 but with less pressure than the pull wheels 40.

The gage 20 against which the sheet S is registered by the bar 16 is set so that it contacts with the bar 16 to prevent the sheet S from entering between the gage 20 and bar 16 (Fig. 5). This side guide mechanism carried by the bracket 40^a may be adjusted transversely of the feeder by the bracket 51 clamped to the bar 7 by the wedge block 52 and cap-screw 53 (Fig. 4). The bracket 40^a may be moved in either direction relatively to the clamped bracket 51 by the knurled nuts 54 (Fig. 1). The sheets S are advanced to this 55 sheet-register mechanism over the feed rollers 55 in the direction of the arrow shown in Fig. 2 by any suitable means.

The operation of this sheet-register mechanism is substantially as follows: The sheet S is forwarded by the rollers 55 until it reaches the position shown in Fig. 5 between the sliding bar 16 and the superposed plate 32 and pull wheels 40; then in timed relation with the cam 23, the wheels 40 and plate 32 drop into contact with the sheet 70 by the action of the springs 46 and 47. The wheels 40 will make contact first and then the heavier tension of the spring 47 will lower the plate 32 until it also bears on the sheet S with a pressure substantially equal to the difference 75 in the respective tensions of these springs 46 and

47. Thereafter the sliding bar 16 is moved to the right (Figs. 1 and 5) by the cam 9 acting through the arm 12 and the sheet S will be carried against the side gage 20 and registered. As the sheet strikes this gage 20 the bar 16 will continue its movement to the right and slide under the sheet as shown in Fig. 6. By this mechanism each sheet 10 is held perfectly flat against the gage 20 by the plate 32 and bar 16 thereby preventing any curling or wrinkling of the sheet margins and also 15 avoiding any bruising or tearing of the edges. The rounded edges of the pull wheels 40 do not interfere with the front or leading edges of the sheets as they are successively advanced by the 20 rollers 55.

15 While it is preferred to use the specific construction and arrangement of parts as shown and described, it will be understood that such construction is not essential and may be varied and modified as may be found desirable or best suited 20 to the machine in which my improved sheet-register is to be employed.

I claim as my invention:

1. A sheet-register comprising a side gage, 25 parallel members between which the sheet is advanced, and means for moving one of said members transversely in parallelism with the sheet to draw the latter against said side gage, said member continuing its transverse movement after the sheet contacts with said side gage. 30

2. A sheet-register comprising a side gage, 35 parallel members between which the sheet is advanced, and means for moving the subjacent member transversely in parallelism with the sheet to draw the latter against said side gage, said member continuing its transverse movement after the sheet contacts with said side gage. 40

3. A sheet-register comprising a side gage, 45 parallel members between which the sheet is advanced, the upper member being held stationary on said sheet, and means for moving the lower member transversely in parallelism with the sheet to draw the latter against the side gage, said member continuing its transverse movement after the sheet contacts with said side gage. 50

4. A sheet-register comprising a side gage, 55 vertically movable rotary means adapted to bear on the sheet, parallel members between which the sheet is advanced, and means for moving one of said members transversely in parallelism with the sheet to draw the latter against said side gage while said rotary means contacts with the sheet, said member continuing its transverse movement after the sheet contacts with said side gage. 60

5. A sheet-register comprising a side gage, 65 vertically movable rotary means adapted to bear on the sheet, parallel members between which the sheet is advanced, and means for moving the subjacent member transversely in parallelism with the sheet to draw the latter against said side gage while said rotary means contacts with the sheet, said member continuing its transverse movement after the sheet contacts with said side gage. 70

6. In a sheet-register, vertically movable freely rotatable means and a plate both adapted to bear on the sheet, and means for sequentially and 75 yieldingly bringing both said freely rotatable means and plate separately into successive contact with the sheet in the order named.

7. In a sheet-register, vertically movable freely rotatable means and a plate both adapted to bear on the sheet, and spring means for sequentially and yieldingly bringing both said freely 75

5 rotatable means and plate separately into successive contact with the sheet in the order named.

8. In a sheet-register, vertically movable freely rotatable means and a plate both adapted to bear on the sheet, and complementary spring-tensioned means for sequentially bringing both said freely rotatable means and plate separately into successive contact with the sheet in the order named.

10 9. In a sheet-register, vertically movable freely rotatable means and a plate both adapted to bear on the sheet, and complementary variably spring-tensioned means for sequentially bringing both said freely rotatable means and plate separately into successive contact with the sheet in the order named.

15 10. In a sheet-register, freely-rotatable means and a plate both adapted to bear on the sheet, and means for yieldingly bringing both said freely rotatable means and plate separately into successive contact with the sheet in the order named under different pressures.

11. In a sheet-register, freely rotatable means and a plate both adapted to bear on the sheet, and means for yieldingly sequentially bringing both said freely rotatable means and plate separately into successive contact with the sheet in the order named under different pressures.

12. In a sheet-register, freely rotatable means and a plate both adapted to bear on the sheet, means for yieldingly bringing both said freely rotatable means and plate separately into successive contact with the sheet in the order named under spring pressures, and means for varying said spring pressures imparted by said freely rotatable means and plate.

13. In a sheet-register, rotary means and a plate both adapted to bear on the sheet, means for sequentially bringing said rotary means and plate into contact with the sheet under spring pressures, and means for interchangeably varying said spring pressures imparted by said rotary means and plate.

14. In a sheet-register, a side gage, rotary means and a plate both adapted to bear on the sheet, a member subjacent to the sheet in par-

5 lelism with said plate, means for bringing said rotary means and plate into successive contact with the sheet in the order named, and means for moving said member transversely beneath, and in parallelism with, the sheet to draw same against said side gage, said member continuing its transverse movement after the sheet contacts with said side gage.

15. In a sheet-register, a side gage, rotary means and a plate both adapted to bear on the sheet, a member subjacent to the sheet in parallelism with said plate, means for sequentially bringing said rotary means and plate into successive contact with the sheet in the order named under spring pressures, and means for thereafter moving said member transversely beneath, and in parallelism with, the sheet to draw same against said side gage, said member continuing its transverse movement after the sheet contacts with said side gage.

20 16. In a sheet-register, rotary means arranged over the sheet, a spring yieldingly forcing said means into contact with the sheet, a plate associated with said rotary means, and a spring of greater tension than said first spring for forcing said plate onto said sheet.

25 17. In a sheet-register, rotary means arranged over the sheet, a spring yieldingly forcing said means into contact with the sheet, a plate associated with said rotary means, a spring of greater tension than said first spring for forcing said plate onto said sheet, and means for bringing said springs into action in the order named.

30 18. In a sheet-register, a side gage, rotary means arranged over the sheet including a spring yieldingly forcing said means into contact with the sheet, a plate associated with said rotary means and having a spring of greater tension than said first spring to force said plate onto the sheet, means for bringing said springs sequentially into action, a member subjacent to the sheet in parallelism with said plate, and means for moving said member transversely beneath the sheet to draw same against said side gage.

45 CHARLES W. HARROLD.
